MEASURING WHEEL WITH EXTENDABLE HANDLE

Charles A. Kenworthy, P.O. Box 151,
Encino, Calif. 91316

Filed June 24, 1968, Ser. No. 12,479

Term of patent 14 years

Int. Cl. D10—08

U.S. Cl. D52—6

FIG. 1 is a front elevational view of a measuring wheel with extendable handle, showing my new design;

FIG. 2 is a front elevational view of same, with the handle in retracted position;

FIG. 3 is a side elevational view thereof with the handle portion shown fragmentarily for convenience of illustration;

FIG. 4 is a rear view of the measuring wheel, with the handle also fragmentarily shown.

I claim:

The ornamental design for a measuring wheel with extendable handle, as shown.
